WASHING MACHINE

Filed April 10, 1925

Fig. 1.

Patented June 15, 1926.

1,588,588

UNITED STATES PATENT OFFICE.

TEUNIS P. KLEYN, OF MUSKEGON, MICHIGAN.

WASHING MACHINE.

Application filed April 10, 1925. Serial No. 22,041.

The present invention relates to washing machines of the class wherein the tub is fixed and the water in the tub is circulated by a propeller. It differs from prior machines of this class in having the entire path of the circulating water wholly within the confines of the tub, instead of partly in the tub and partly in a conduit extraneous to the tub, as has been proposed heretofore. The chief objects of the invention are to provide a simple machine of the class mentioned, to cleanse solely by currents of water supplied with soap or other cleansing agent, to aerate the articles being cleansed, to construct and arrange the machine parts so that the articles will engage only fixed parts, to positively force the air and water through the clothes being washed, to provide a simple arrangement of gears, and to make all the parts readily available for replacement and repair.

The various features and advantages of the invention will be more fully understood upon reference to the following detailed description, taken in connection with the accompanying drawing, and the scope of the invention will be particularly pointed out in the appended claims.

In said drawing, Fig. 1 is a central vertical section of a washing machine constructed in accordance with the present invention, associated with a centrifugal drier, all mounted upon a common frame; Fig. 2 is a plan view of a central portion of the upper bottom of the tub showing the associated tube and the propeller therein for producing the circulation of the water in the tub; Fig. 3 is a plan view of a portion of the wash tub showing the positions of a clutch control lever, hose clip and air supply pipe; and Fig. 4 is a side elevation of a portion of the same tub showing the clutch control lever thereon in elevation. In these views like characters refer to like parts.

Referring to the drawing in detail, 10 designates legs of the machine united by a frame member 11. The frame structure may be variously arranged, and obviously four legs will be provided, although but two are shown. The members 11 between the different pairs of legs may also be connected by transverse members 11^a. Any desired number of such interconnecting members may be employed.

The wash tub 12 and the drier tub 13 are secured to and supported upon the frame

structure, the two tubs being tangent at the point of contact shown in Fig. 1. The vertical walls of the tubs 12 and 13 are circular in horizontal section and unite at their lower ends with more or less conical bottoms 14 and 15. The wash tub bottom 14 has a flat central portion 15'. A perforated upper bottom 16 is secured at its upper edge to the interior of the tub walls and is upturned at its lower end to provide a tubular aperture into which the tube or conduit 17 is fitted. The greater portion of the bottom 16 is spherical in curvature, as clearly illustrated. The tube 17 is secured at its upper end to the upturned portion 18 of the upper bottom 16. The latter is provided with a large number of perforations 19. The lower end of the tube 17 terminates at the flat central portion 15' of the bottom 15 of the tub and is there suitably secured. The interior of the tube 17 is in communication with the space 20 between the bottoms 14 and 16 through apertures 21 in the tube 17. The upper end of this tube is threaded internally for the reception of an extension tube 17' which is cooperatively threaded externally at its lower end. In ordinary washing operations the extension tube 17' will be removed and the tube 17 alone will suffice to give the necessary circulation. But in washing heavy articles, as rugs, blankets, etc., I preferably use the extension tube. Thus, whether the tube 17' be used or not, a passage is provided from the space 20 below the bottom 19 to the space 22 above the upper bottom 16. A shaft 23 extends vertically upward into the tube 17 and is provided at its upper end with a propeller 24, the latter being rigidly secured to the shaft. To provide a watertight connection the shaft 23 passes through a stuffing box 25 in the portion 15' of the tub bottom. The lower end of the shaft 23 is provided with a bevel gear 26 which meshes with a driving bevel gear 27 on a horizontal shaft 28. The latter is journaled in hangers 29 and 30 mounted upon certain of the frame members. An electric motor 31 is also carried by the frame members 11^a of the machine and is positioned so as to have its shaft connected to shaft 28 by a coupling 32. Besides the openings 21 in the tube 17, there is an air supply opening 33 toward the upper end of the tube. This opening connects directly with the interior of an air supply pipe 34 which preferably follows the under side of the up-

per bottom 16 and the vertical wall of the tub terminates at a point well above the water line 35. The upper end of the pipe 34 is provided with a valve 36 by which the air supply to the tube 17 may be regulated or, if desired, absolutely cut off. The top of the wash tub 12 is provided with an inwardly extending flange 37. The inner edge of this flange is upturned to provide a vertical flange 38. A cover 39 having a cooperating downwardly extending flange 40 and a central handle 41, serves to close the opening.

The drier tub 13 is provided with similar flanges 42 and 43, and a similar cover 44, having a peripheral flange 45, and a handle 46. The tub 13 is also provided with a stuffing box 47 through which a vertical shaft 48 extends. This shaft carries the drier basket 49 which rotates within the tub 13. The lower end of the shaft 48 is journaled in a horizontal arm 50 upon the hanger 30, and is held from dropping by a fixed collar 51 upon the shaft. The lower end of the shaft is provided with a bevel gear 52 which meshes with a similar bevel pinion 53 on the shaft 28.

The wash tub 12 has the horizontal portion 15' of its bottom apertured for a drain connection which, in the present instance, includes a valve 54 connected with a drain hose 55. The water from the tub 12 is drawn off by opening the valve 54 and allowing the water to pass through the hose 55. In the case of the drier tub 13, the bottom 15 of the tub is apertured, and the hose 56 is directly connected to the connection provided at the aperture. The hose 56 is of sufficient length to allow its upper end to be brought to the top of the tub 13 and there held in place by a clip 57 when it is not desired to drain the tub. When the tub is to be drained then the hose 56 is lowered so as to lie below the bottom of the tub and then the water in the latter will run off. Similarly, when not in use, the hose 55, which is of sufficient length for the purpose, may be held up away from the floor by passing its upper end between the yielding members of a clip 57' on the tub 12.

In order to permit the washing machine to run independently of the drier, and the drier independently of the washing machine, I provide clutches 58 and 59 in association with the pinions 53 and 27 respectively, upon the shaft 28. The clutch members may be actuated in the case of clutch 58 by a lever 60, and in the case of clutch 59 by a lever 61. The lever 61 is connected by a link 62 to a bell crank lever 63 pivoted to the frame of the machine. The lever 63 is in turn connected by a link 64 to a manually operated bell crank lever 65 pivoted upon a bracket secured to the side of the tub 12 in a position convenient to the one using the machine. A

retaining segment 66 is also secured to the tub 12 and cooperates with a latch 67 on the handle of the lever 65 to hold the latter in proper positions. The lever 60 is similarly actuated by a hand lever 65' of the same construction as the lever 65 but located upon the tub 13, the connections being provided through the similar link 62', bell crank lever 63' and link 64'. A similar segment 66' and a similar latch 67' are associated with the lever 65'.

In operation, the tub 12 is filled to the water line 35 with water supplied with soap or other cleansing agent in solution. If blankets and heavy clothes are to be washed then the extension tube 17' is left in place; otherwise it is removed. Then the clothes to be washed are placed in this water. The motor 31 is then started and the clutch 59 thrown to drive the shaft 23. The rotation of the latter will cause the propeller 24 to force water upward through the tube 17, or tubes 17 and 17' as the case may be. Thus the water in the space 20 will be carried up through the tube into the space 22. In the latter there will be a central upward current which divides into radiating currents which pass downward near the wall of the tub and thence through the perforations 19 into the space 20, as indicated generally by the arrows in Fig. 1. The repeated application of these currents of water to the clothes will thoroughly wash them. Of course, ordinarily, too, air from the outside of the tub will be supplied through the pipe 34 to the opening 33 in the tube 17, and thus the central rush of water will take up the air thus supplied, and the water well mixed with air will be applied to the clothes. Thus the latter will be aerated while being cleansed. When it is desired to stop the washing operation, it is only necessary to throw out the clutch 59 or, if desired, stop the motor 31.

At the conclusion of the washing operation, the cover 39 will be removed and the clothes lifted from the tub 12 into the basket 49 in the drier tub 13. The clutch 58 will then be thrown, after having started the motor 31, if it has been idle, and shaft 48 with the drying basket 49 rotated. The gear wheels 52 and 53 are proportioned so as to cause the basket 49 to rotate at high speed. In order to carry off the water which is forced from the clothes in the basket the drain hose 56 is lowered so as to lie below the bottom of the tub. When the clothes have been sufficiently dried, the clutch 58 may be thrown out so as to disconnect the shaft 48. Then the clothes may be removed from the basket 49. At the conclusion of the washing operation, the tub 12 may be drained by lowering hose 55 and opening valve 54.

From the above description it will be seen that I have provided a washing machine in

which all paths of the circulating water lie wholly within the confines of the tub. Obviously, this might be accomplished with a structure which would be modified in certain respects from that illustrated. I, therefore, do not wish to be limited to the specific disclosure, but aim to cover by the terms of the appended claims all such alternations and modifications as rightly come within the spirit and scope of my invention.

What I claim as new and desire to secure by a patent of the United States is:

1. A washing machine comprising a tub, an upper perforated bottom fixed in said tub and spaced from the tub bottom, a central tube extending through said upper bottom and communicating with the space between said bottoms, an air supply pipe terminating at its outer end at a point above the water line of the tub and at its inner end communicating with said central tube, a shaft extending through the tub bottom into said tube, a propeller on said shaft within said tube, and means for driving said shaft.

2. A washing machine comprising a tub having a conical bottom, an upper perforated curved bottom spaced from said conical bottom, a central cylindrical tube extending through said upper bottom and communicating with the space between said bottoms and terminating above said upper bottom, a shaft extending through said conical bottom into said tube, a propeller mounted on said shaft, an air supply pipe opening into said tube and extending along the under

side of said upper bottom and along the outside of the tub wall to a point near the top of the tub, a valve in said air supply pipe, and a motor for driving said shaft.

3. A washing machine comprising a tub having a conical bottom, an upper perforated curved bottom spaced from said conical bottom, a central cylindrical tube extending through said upper bottom and communicating with the space between said bottoms and terminating above said upper bottom, an extension tube removably secured at its lower end to the upper end of said central cylindrical tube, a shaft extending through said conical bottom into said tube, a propeller mounted on said shaft, an air supply pipe opening into said tube and extending along the under side of said upper bottom and along the outside of the tub wall to a point near the top of the tub, a valve in said air supply pipe, and a motor for driving said shaft.

4. A washing machine comprising a tub, an upper perforated bottom fixed in said tub and spaced from the tub bottom, a central conduit communicating between the spaces in the tub above and below said upper bottom, and a power driven propeller in said conduit for driving water upward through the conduit, said central conduit being of variable length to provide for the washing of light and heavy clothes.

In witness whereof, I hereunto subscribe my name this 6th day of April, 1925.

TEUNIS P. KLEYN.
